UNITED STATES PATENT OFFICE

1,972,551

REFRIGERATING APPARATUS

Ernest Dickey, Dayton, Ohio, assignor to Frigid-air Corporation, Dayton, Ohio, a corporation of Delaware

Application February 26, 1932, Serial No. 595,359
Renewed November 2, 1933

18 Claims. (Cl. 62—126)

This invention relates to refrigerating apparatus and particularly to evaporators of such apparatus.

An object of my invention is to provide a sheet metal evaporator construction having, between the liquid refrigerant inlet and the gaseous refrigerant outlet connections thereof, an improved refrigerant flow circuit including a portion connected in series with the inlet connection and another portion including interconnected passages connected in parallel circuit relation with the outlet connection.

In carrying out the foregoing object, it is a further object of my invention to form one portion and at least a part of the other portion of the refrigerant flow circuit, through the evaporator, between sheet metal members bent to provide walls of an enclosure and to utilize the portion of the refrigerant flow circuit connected in series with the refrigerant inlet connection, as a freezing portion or zone and to utilize the passages of the flow circuit, connected in parallel circuit relation with the outlet connection, as a refrigerant distributing portion or air cooling zone for the evaporator.

Further objects and advantages of the present invention will be apparent from the following description, reference being had to the accompanying drawings, wherein a preferred form of the present invention is clearly shown.

In the drawings:

Fig. 1 discloses a refrigerator cabinet having my improved evaporator installed therein;

Fig. 2 is an enlarged front view of my improved evaporator having the door thereof removed and showing compartments with ice trays mounted therein;

Fig. 3 is a side elevational view of the evaporator shown in Fig. 2;

Fig. 4 is a horizontal sectional view through the evaporator and is taken on the line 4—4 of Fig. 2;

Fig. 5 is a vertical sectional view through the evaporator taken on the line 5—5 of Fig. 3;

Fig. 6 is a vertical sectional view through another portion of the evaporator and is taken on the line 6—6 of Fig. 3;

Fig. 7 is a bottom view of the evaporator disclosed in Fig. 2 showing manifolds therein;

Fig. 8 is a vertical sectional view through another portion of the evaporator and taken on the line 8—8 of Fig. 3;

Fig. 9 is a view similar to Fig. 2 and shows the front of a modified form of evaporator constructed according to the invention;

Fig. 10 is a side elevational view of the modified form of evaporator shown in Fig. 9;

Fig. 11 is a bottom view of the evaporator disclosed in Fig. 9 showing manifolds formed therein;

Fig. 12 is a vertical sectional view through the modified form of evaporator and is taken on the line 12—12 of Fig. 10; and

Fig. 13 is a vertical sectional view through another portion of the modified form of the evaporator taken on the line 13—13 of Fig. 10.

For the purpose of illustration, I have shown in Fig. 1 of the drawings an evaporator 20 constructed according to my invention mounted in a refrigerator cabinet 21 of any suitable construction. Preferably the cabinet comprises a food storage compartment 22 having a door 23 providing access thereto and a machine compartment (not shown) disposed above the compartment 22. The refrigerant liquefying unit of 75 the refrigerating system, connected with the evaporator 20, may be of any suitable type and is adapted to be mounted in the machine compartment disposed above compartment 22. Mechanical refrigerating apparatus of the construction disclosed are well known to those familiar with the art and herein needs no further description.

Since my invention is directed to a finished evaporator structure the method of forming my improved evaporator will not be herein dealt with in detail. My evaporator is produced by uniting in any suitable manner superimposed sheet metal members 25 and 26 (see Figs. 5, 6 and 8) to provide a double wall structure having passages 90 formed between the members. The double sheet metal members 25 and 26 are bent to form a double metal top wall 27, a bottom wall 28 and side walls 29 and 31 of a horizontally disposed enclosure. A liquid refrigerant inlet conduit connection 32 and a gaseous refrigerant outlet connection 33 are connected to the top wall 27 of evaporator 20 and communicate with the space between the sheet metal members. The refrigerant connection 32 is connected with a refrigerant control device (not shown) which controls or governs the flow of liquid refrigerant to the evaporator. This device may be in the form of an expansion or float valve and preferably a high side float valve well known in the art. The refrigerant connection 33 leads from the evaporator 20 to the crankcase or suction side of a compressor usually employed in refrigerant liquefying units for withdrawing gaseous or vaporized refrigerant from the evaporator. In order to provide a freez-

110

- ing portion and a refrigerant distributing or air cooling portion for the evaporator, a refrigerant duct 35 is formed by and located between the sheet metal members 25 and 26 at the front of the evaporator. Duct 35 communicates with the liquid refrigerant inlet connection 32 and extends therefrom across the top wall 27, side walls 29 and 31 and across at least a portion of the bottom wall 28 of the enclosure (see Fig. 5). The freezing portion of the refrigerant flow circuit or of the evaporator includes a means in the form of a shelf 36 which divides the enclosure formed by the double sheet metal walls 27, 28, 29 and 31 into two superimposed compartments 37 and 38. The shelf means 36 comprises two superimposed sheet metal plates or members 41 and 42 (see Fig. 8) secured together in any suitable manner. The lower plate or member 42 of shelf 36 has formed therein depressions which, when the plates 41 and 42 are secured together, provide a refrigerant passage or duct leading from the duct 35 formed in walls 27, 28, 29 and 31, horizontally through the enclosure. This refrigerant duct in shelf 36 includes a passage 43 communicating with the refrigerant duct 35, formed in each side wall 29 and 31 of the enclosure, by hollow bushings 44 secured to the inner sheet metal member 25 and to the shelf 36 (see Fig. 4). A sinuous or serpentine passage 45 also formed by and located between the sheet metal members 41 and 42 of shelf 36 has its one end 46 connected with the passage 43. The opposite end 47 of the serpentine passage 45 is connected with a passage 48 in shelf 36 which passage is similar to passage 43 formed therein. A refrigerant duct or conduit 51 formed by and located between the sheet metal members 25 and 26 forming the walls 27, 28, 29 and 31 is disposed at the rear of the evaporator. By reference to Fig. 6 of the drawings it may be seen that refrigerant conduit 51 is similar to refrigerant duct 35 and extends around the walls 27, 28, 29 and 31 of the enclosure. This refrigerant conduit 51 communicates with the passage 48 in shelf 36 on each side of the enclosure by connecting bushings 44a secured to the inner sheet metal member 25 of the enclosure walls. The refrigerant conduit 51 communicates at its lower ends, located in the bottom wall 28 of the enclosure, with a pair of manifolds 53 and 54 formed by and located between the sheet metal members 25 and 26. A plurality of conduits or passages 55 formed by and located between the members 25 and 26 are connected with the manifold 53 and extend around at least a portion of the bottom and top walls 28 and 27 and traverses the side wall 29 of the enclosure. Another plurality of refrigerant ducts or the conduits 56 similar to ducts 55 communicate with the manifold 54 and extend around at least a portion of the bottom and top walls 28 and 27 and traverses the side wall 31 of the enclosure. Each set of the plurality of conduits or passages 55 and 56 are interconnected, or communicate with the gaseous refrigerant outlet connection 33 of the evaporator, by means of a manifold 58 formed by and located between the members 25 and 26 in the top wall 27 of the horizontally disposed enclosure.
- From the above description of the refrigerant passages, ducts and conduits it may be seen that I have provided a refrigerant flow circuit through the sheet metal evaporator 20, between the refrigerant inlet and outlet connections located in the top wall thereof, which includes an extended portion connected in series with the liquid refrigerant inlet connection 32 and another por-

tion connected in parallel circuit relation and communicating with the gaseous refrigerant outlet connection 33. More fully explaining this refrigerant flow circuit, between the refrigerant connections 32 and 33 of the evaporator 20, the portion connected in series with inlet 32 includes the passage or duct 35 formed in the walls of the enclosure, conduits or passages 43, 45 and 48 formed in the shelf 36, conduit or duct 51 formed in the wall of the enclosure and the manifold passages 53 and 54 formed between the members of the bottom wall of the enclosure. The portion of the refrigerant flow circuit connected in parallel circuit relation includes the plurality of ducts or passages 55 and 56 extending from the manifolds 53 and 54 to the manifold 58 having the refrigerant outlet 33 connected thereto.

In defining the foregoing mentioned passages, conduits or ducts it is to be understood that each passage is sealed about its edges by uniting the metal members 25 and 26 between the passages formed therebetween. Since refrigerant is first circulated from the liquid refrigerant inlet connection 32 in a series path to or through the shelf means 36 this shelf provides a quick freezing support or freezing zone for ice trays or the like. Also since refrigerant is circulated in a series path directly from the shelf means 36 to or through the manifolds 53 and 54 located in the bottom wall 28 of the enclosure this bottom wall 28 also provides a quick freezing support or freezing zone for ice trays or the like. After passing through the support or shelf 36 and bottom wall 28 of the enclosure the refrigerant is distributed by manifolds 53 and 54 to the passages 55 and 56. These passages 55 and 56 being formed in the walls of the enclosure to provide air cooling portions for the evaporator.

In Figs. 9, 10, 11, 12 and 13 of the drawings I have shown a modified evaporator construction in which the enclosure of the evaporator is not divided into a plurality of compartments. This modified form of evaporator construction is adapted for installation in small refrigerator cabinets and is adapted to receive ice trays on the bottom wall thereof only. It will be apparent from the following description that this modified form of evaporator also comprises the refrigerant flow circuit heretofore described, with reference to evaporator 20, while the portion of the flow circuit connected in series with the inlet connection is not of as great a length as in the case of evaporator 20. The evaporator 20a in Figs. 9, 10, 11, 12 and 13 of the drawings includes superimposed sheet metal members or plates 25a and 26a (see Figs. 12 and 13) secured together and bent to form a horizontally disposed freezing enclosure 60 comprising the double metal walls 27a, 28a, 29a and 31a. Refrigerant inlet and outlet connections 32a and 33a respectively are located in the top wall 27a of the evaporator 20a. A refrigerant duct or conduit 35a communicates with the refrigerant inlet connection 32a and is formed by and located between the sheet metal members 25a and 26a and extends around the walls 27a, 28a, 29a and 31a (see Fig. 12). One end of the duct 35a communicates with a manifold 53a formed by and located between the members 25a and 26a in the bottom wall 28a of evaporator 20a. The other end of duct 35a communicates with a manifold 54a formed by and located between the members 25a and 26a in the bottom wall 28a of evaporator 20a. A plurality of refrigerant passages or con-

- duits 55a (see Fig. 13) formed by and located between the members 25a and 26a extend around the walls 27a, 28a and 29a of the enclosure 60. Another plurality of refrigerant passages or conduits 56a (see Fig. 13) formed by and located between the members 25a and 26a extend around the walls 27a, 28a and 31a of the enclosure 60. Each set of the plurality of passages 55a and 56a communicate with the manifolds 53a and 54a respectively and terminate in a manifold passage 58a formed by and located between the members 25a and 26a in the top wall 27a of the evaporator. The gaseous refrigerant outlet connection 33a communicates with the manifold 58a.
- 15 From the above description of the construction of the modified form of evaporator 20a and the refrigerant passages, conduits or ducts formed therein it may be seen that this form of evaporator also comprises a refrigerant flow circuit, between the refrigerant inlet and outlet connections located in the top wall thereof, which includes an extended portion connected in series with the liquid refrigerant inlet connection 32a and another portion connected in parallel circuit relation and communicating with the gaseous refrigerant outlet connection 33a. To fully point out the refrigerant flow circuit through this modified evaporator 20a the refrigerant circuit connected in series with the inlet connection 32a includes the duct 35a and the manifolds 53a and 54a communicating with the duct 35a. The portion of the refrigerant flow circuit connected in parallel circuit relation with the gaseous refrigerant outlet connection 33a includes the refrigerant passages or conduits 55a and 56a and the manifold passage 58a. It being understood that the refrigerant passages, conduits or ducts are all sealed around their edges by securing the metal members 25a and 26a together between the ducts formed therebetween. Thus the bottom wall 28a of evaporator 20a or enclosure 60 provides a quick freezing support or freezing zone for ice trays by virtue of receiving refrigerant directly from the refrigerant inlet. The refrigerant ducts or passages 55a and 56a form an air cooling portion for the evaporator by virtue of refrigerant being distributed by the manifolds 53a and 54a to these ducts or passages.
- 40 The evaporator 20 or 20a may, if desired, include a door 61 pivotally mounted thereto by hinges or the like 62 to close the enclosure at the front of the evaporator and to provide access to the interior of the enclosure 60 or compartments 37 and 38. A cover 63 may also be mounted on the evaporator 20 or 20a in any suitable manner if desired to close the rear end of the enclosure. Mounting means for the evaporator 20 or 20a comprise studs 65 welded or otherwise secured to the top wall 27 or 27a of the evaporator. It is to be understood that the entire evaporator 20 or 20a may be coated or plated with any suitable material, for example, it may be coated with vitreous enamel or it may be chrome plated.
- 45 By providing a sheet metal evaporator having means formed in a plurality of walls thereof for circulating a refrigerant from an inlet connection located in the top wall of the evaporator to a lower portion thereof, and to a fast freezing support within the evaporator, I have eliminated a refrigerant conducting pipe separate from the evaporator, and usually extending around the evaporator from its supporting wall. The omission of a pipe separate from the evaporator and ordinarily extending therearound and to a lower portion thereof in addition to improving the general appearance of the interior of the refrigerator cabinet also permits walls of the evaporator to be cleaned without interference.
- 50 From the foregoing it is apparent that I have provided a novel sheet metal evaporator having an improved and efficient refrigerant flow circuit formed in the walls of the evaporator between the refrigerant inlet and outlet connections thereof which includes a portion providing a quick freezing or freezing zone and another portion providing an air cooling zone for the evaporator.
- 55 While the form of embodiment of the invention as herein disclosed, constitutes a preferred form, it is to be understood that other forms might be adopted, all coming within the scope of the claims which follow.
- 60 What is claimed is as follows:
1. An evaporator comprising superimposed sheet metal members bent to form a plurality of walls of a freezing enclosure, a liquid refrigerant inlet connection and a gaseous refrigerant outlet connection in the top wall of said enclosure, a manifold passage formed by and located between said sheet metal members in another wall of said enclosure, a refrigerant conveying duct having a portion thereof formed by and located between said sheet metal members and communicating with said inlet connection, a plurality of refrigerant conveying conduits formed by and located between said sheet metal members and communicating with said outlet connection, said refrigerant duct including means communicating with said manifold passage and said manifold passage communicating with said plurality of refrigerant conduits to provide between the inlet and outlet connections of said evaporator a refrigerant flow circuit including an extended portion in series with said inlet connection and another portion in parallel circuit relation with 115 said outlet connection, the means permitting communication of said refrigerant duct with said manifold passage including means dividing said enclosure into superimposed compartments.
- 115 2. An evaporator comprising superimposed sheet metal members bent to form four walls of an elongated horizontally disposed enclosure, a liquid refrigerant inlet connection and a gaseous refrigerant outlet connection in the top wall of said enclosure, a plurality of refrigerant conveying ducts formed by and located between said sheet metal members and traversing at least a portion of a side, top and bottom wall of said enclosure, said plurality of refrigerant ducts communicating with one another and with said outlet connection, a refrigerant conveying conduit having at least a portion thereof formed by and located between said sheet metal members, said refrigerant conduit traversing at least a portion of a side, top and bottom wall of said enclosure, and said refrigerant conduit communicating with said refrigerant ducts and with said inlet connection to provide between said refrigerant inlet and outlet connections of said evaporator a refrigerant flow circuit including an extended portion in series with said inlet connection and another portion in parallel circuit relation with said outlet connection, said communication of said refrigerant conduit with said refrigerant ducts including means dividing said enclosure into superimposed compartments.
- 120 3. An evaporator comprising superimposed sheet metal members bent to form four walls of an elongated horizontally disposed freezing en-

- closure, a liquid refrigerant inlet connection and a gaseous refrigerant outlet connection in the top wall of said enclosure, a plurality of manifolds formed by and located between said sheet metal members in the bottom wall of said enclosure, two passages each having at least a portion thereof formed between said sheet metal members, one of said passages communicating with said inlet connection and with one of said manifolds and the other of said passages communicating with said inlet connection and with the other of said manifolds to provide paths of flow for refrigerant from said inlet connection to said manifolds, two sets of a plurality of conduits formed by and located between said sheet metal members and traversing at least a portion of a plurality of walls of said enclosure, one set of said conduits communicating in parallel circuit relation with one of said manifolds and the other set of said conduits communicating in parallel circuit relation with the other of said manifolds, and both sets of said conduits being in open communication with said gaseous refrigerant outlet connection.
- 25 4. An evaporator comprising superimposed sheet metal members bent to form four walls of an elongated horizontally disposed freezing enclosure, a liquid refrigerant inlet connection and a gaseous refrigerant outlet connection in the top wall of said enclosure, a plurality of manifolds formed by and located between said sheet metal members in the bottom wall of said enclosure, two passages each having at least a portion thereof formed between said sheet metal members, one of said passages communicating with said inlet connection and with one of said manifolds and the other of said passages communicating with said inlet connection and with the other of said manifolds to provide paths of flow for refrigerant from said inlet connection to said manifolds, two sets of a plurality of conduits formed by and located between said sheet metal members and traversing at least a portion of a plurality of walls of said enclosure, one set of said conduits communicating in parallel circuit relation with one of said manifolds and the other set of said conduits communicating in parallel circuit relation with the other of said manifolds, both sets of said conduits being in open communication with said gaseous refrigerant outlet connection, and means dividing the enclosure into superimposed compartments, said means having a refrigerant duct provided therein and forming a portion of said passages.
- 55 5. An evaporator comprising superimposed sheet metal members bent to form a plurality of walls of an enclosure, a liquid refrigerant inlet connection and a gaseous refrigerant outlet connection for said evaporator, a plurality of refrigerant conveying ducts formed by and located between said sheet metal members in at least one wall of said enclosure to provide said evaporator with an air cooling zone, said plurality of refrigerant ducts communicating with one another and with said outlet connection, a refrigerant conveying conduit extending through said enclosure to provide a freezing zone therein, said refrigerant conduit communicating with said refrigerant ducts and with said inlet connection to provide between said refrigerant inlet and outlet connections of said evaporator a refrigerant flow circuit including an extended portion in series with said inlet connection and another portion in parallel circuit relation with said outlet connection.
- 60 6. An evaporator comprising superimposed sheet metal members bent to form a plurality of walls of an enclosure, a liquid refrigerant inlet connection and a gaseous refrigerant outlet connection for said evaporator, a plurality of refrigerant conveying ducts formed by and located between said sheet metal members in at least one wall of said enclosure to provide said evaporator with an air cooling zone, said plurality of refrigerant ducts communicating with one another and with said outlet connection, means dividing said enclosure into a plurality of compartments, a refrigerant conveying conduit formed in said means to provide a freezing zone within said enclosure, said refrigerant conduit communicating with said refrigerant ducts and with said inlet connection to provide between said refrigerant inlet and outlet connections of said evaporator a refrigerant flow circuit including an extended portion in series with said inlet connection and another portion in parallel circuit relation with said outlet connection.
- 65 7. An evaporator comprising superimposed sheet metal members bent to form a plurality of walls of an enclosure, a liquid refrigerant inlet connection and a gaseous refrigerant outlet connection for said evaporator, a plurality of refrigerant conveying ducts formed by and located between said sheet metal members in at least one wall of said enclosure to provide said evaporator with an air cooling zone, said plurality of refrigerant ducts communicating with one another and with said outlet connection, means dividing said enclosure into a plurality of compartments, a refrigerant conveying conduit formed in said means and providing a freezing zone within said enclosure, said refrigerant conduit including a portion formed by and located between said sheet metal members in at least one wall of said enclosure, one end of said refrigerant conduit being in communication with said refrigerant ducts and the opposite end thereof being in communication with said inlet connection to provide between said refrigerant inlet and outlet connections of said evaporator a refrigerant flow circuit including an extended portion in series with said inlet connection and another portion in parallel circuit relation with said outlet connection.
- 70 8. An evaporator comprising superimposed sheet metal members bent to form four walls of an enclosure, a liquid refrigerant inlet connection and a gaseous refrigerant outlet connection in the top wall of said enclosure, a plurality of refrigerant conveying ducts formed by and located between said sheet metal members in a plurality of walls of said enclosure to provide said evaporator with an air cooling zone, said plurality of refrigerant ducts communicating with one another and with said outlet connection, a refrigerant conveying conduit extending horizontally through said enclosure to divide the enclosure into two superimposed sharp freezing compartments, said refrigerant conduit being in communication with said refrigerant ducts and with said inlet connection to provide between said refrigerant inlet and outlet connections of said evaporator a refrigerant flow circuit including an extended portion in series with said inlet connection and another portion in parallel circuit relation with said outlet connection.
- 75 9. An evaporator comprising superimposed sheet metal members bent to form four walls of an enclosure, a liquid refrigerant inlet connection and a gaseous refrigerant outlet connection in the top wall of said enclosure, a plurality of

- refrigerant conveying ducts formed by and located between said sheet metal members in a plurality of walls of said enclosure and communicating with said outlet connection to provide said 5 evaporator with an air cooling zone, a manifold formed by and located between said sheet metal members in the bottom wall of said enclosure, each of said refrigerant conveying ducts communicating with said manifold, a refrigerant conveying conduit extending horizontally through said enclosure to divide the enclosure into two superimposed sharp freezing compartments, said refrigerant conduit communicating with said manifold and with said inlet connection to provide 10 between said refrigerant inlet and outlet connections of said evaporator a refrigerant flow circuit including an extended portion in series with said inlet connection and another portion in parallel circuit relation with said outlet connection. 15
10. An evaporator comprising superimposed sheet metal members bent to form a plurality of walls of a freezing enclosure, a liquid refrigerant inlet connection and a gaseous refrigerant outlet connection in the top wall of said enclosure, a manifold passage formed by and located between said sheet metal members in one wall of said enclosure and communicating with said outlet connection, a second manifold passage formed 20 by and located between said sheet metal members in another wall of said enclosure, a refrigerant conveying duct having a portion thereof formed by and located between said sheet metal members and communicating with said inlet connection, a plurality of refrigerant conveying conduits formed by and located between said sheet metal members and communicating with said first named manifold passage, said refrigerant duct including means communicating with said second 25 named manifold passage, and said second named manifold passage communicating with said plurality of refrigerant conduits to provide between the inlet and outlet connections of said evaporator a refrigerant flow circuit including an extended portion in series with said inlet connection and another portion in parallel circuit relation with said outlet connection, a portion of the means permitting communication of said refrigerant duct with said second named manifold 30 passage including means dividing said enclosure into superimposed compartments and providing a refrigerated support within the enclosure adapted to receive a receptacle to be cooled. 35
11. An evaporator comprising superimposed sheet metal members bent to form a plurality of walls of a freezing enclosure, a liquid refrigerant inlet connection and a gaseous refrigerant outlet connection in the top wall of said enclosure, a manifold passage formed by and located 40 between said sheet metal members in the top wall of said enclosure and communicating with said outlet connection, a second manifold passage formed by and located between said sheet metal members in the bottom wall of said enclosure, a refrigerant conveying duct having a portion thereof formed by and located between said sheet metal members and communicating with said inlet connection, a plurality of refrigerant conveying conduits formed by and located between said sheet metal members and communicating with said first named manifold passage, said refrigerant duct including means communicating with said second named manifold passage 45 including means dividing said enclosure into superimposed compartments and providing a refrigerated support within the enclosure adapted to receive a receptacle to be cooled. 50
12. An evaporator comprising superimposed metallic sheet-like portions bent to form a plurality of walls of a freezing compartment, a liquid refrigerant inlet connection and a gaseous refrigerant outlet connection both in one wall of said compartment, a plurality of manifolds formed by and located between said sheet-like portions in a wall other than the wall in which the inlet and outlet connections communicate, two passages each having at least a portion thereof formed by and located between said sheet-like portions, one of said passages communicating with said inlet connection and with one of said manifolds and the other of said passages communicating with said inlet connection and with the other of said manifolds to provide paths of flow for refrigerant from said inlet connection to said manifolds, two sets of a plurality of conduits formed by and located between said sheet-like 55 portions and traversing at least a plurality of walls of said compartment, one set of said conduits communicating in parallel circuit relation with one of said manifolds and the other set of said conduits communicating in parallel circuit relation with the other of said manifolds, and both sets of said conduits being in open communication with said gaseous refrigerant outlet connection. 60
13. An evaporator comprising superimposed metallic sheet-like portions bent to form a plurality of walls of a freezing compartment, a header formed by and located between said sheet-like portions in one wall of said compartment, a gaseous refrigerant outlet connection communicating with said header, a liquid refrigerant inlet connection in the same wall in which the header is formed, a plurality of manifolds formed by and located between said sheet-like portions in a wall of said compartment other than the wall in which said header is formed, two passages each having at least a portion thereof formed by and located between said sheet-like portions, one of said passages communicating with said inlet connection and with one of said manifolds and the other of said passages communicating with said inlet connection and with the other of said manifolds to provide paths of flow for refrigerant from said inlet connection to said manifolds, two sets of a plurality of conduits formed by and located between said sheet-like portions and traversing at least a portion of a plurality of walls of said compartment, one set of said conduits communicating in parallel circuit relation with one of said manifolds and the other set of said conduits communicating in parallel circuit relation with the other of said manifolds, and both sets of said conduits being in open communication with said header. 65
14. An evaporator for refrigerating apparatus comprising sheet metal portions cooperating with one another to provide a refrigerant passage therebetween, said cooperating sheet metal portions being arranged to provide a portion for cooling air adapted to flow over said evaporator and 70
- 75

- being formed to provide a plurality of walls of a sharp freezing zone, sheet metal portions cooperating with one another to provide a refrigerant duct therebetween and arranged within said freezing zone to form a shelf for supporting a receptacle, the sheet metal portions of said shelf being separate from and independent of the sheet metal portions of the air cooling portion of the evaporator, means cooperating with the shelf 5 80 and with the walls of the freezing zone for spacing the major portion of the shelf from the walls of the freezing zone, said means comprising a conduit communicating with the refrigerant duct in said shelf and with the refrigerant passage in the walls of said freezing zone, said conduit means being formed of a material separate from and independent of the sheet metal portions of the evaporator and the shelf, and means communicating with the refrigerant duct in said shelf for circulating refrigerant through said shelf duct and thence through said conduit to the refrigerant 10 85 passage in the wall of said freezing zone. 15 90
- 10 15. An evaporator comprising superimposed sheet metal portions arranged to form a plurality of walls of a sharp freezing compartment, a liquid refrigerant inlet connection and a gaseous refrigerant outlet connection in the top wall of said compartment, a manifold passage formed by and located between said sheet metal portions in a wall of said compartment other than the top wall thereof, a second manifold passage formed by and located between said sheet metal portions in a 20 100 wall of said compartment other than the top wall thereof, a refrigerant conveying duct having a portion thereof formed by and located between said sheet metal portions and communicating with said inlet connection, two sets of refrigerant 25 105 conveying passages formed by and located between said sheet metal portions and communicating with said outlet connection, said refrigerant duct communicating with each of said manifold passages and each of said manifold passages communicating with one of the sets of said refrigerant 30 110 conveying passages for directing refrigerant downwardly from said inlet connection to each of said manifold passages and thence upwardly in multiple through said refrigerant conveying 35 115 passages to said outlet connection. 40 120
16. An evaporator for refrigerating apparatus comprising sheet metal portions cooperating with one another to provide a refrigerant passage therebetween, said cooperating sheet metal portions being arranged to provide a portion for cooling air adapted to flow over said evaporator and being formed to provide a plurality of walls of a sharp freezing zone, sheet metal portions cooperating with one another to provide a refrigerant duct therebetween and arranged within said freezing zone to form a shelf for supporting a receptacle, the sheet metal portions of said shelf being separate from and independent of 45 125
